COVER FASTENING MEANS

Harry M. Badger, New Britain, Conn., assignor to
 Landers, Frary & Clark, New Britain, Conn., a
 corporation of Connecticut

Application May 21, 1947, Serial No. 749,417

3 Claims. (Cl. 220—57)

1

The present invention relates to cover fastening means for containers, and more particularly to a quickly and easily engageable and disengageable cover fastening means for containers which is constructed and arranged to provide a tensioned resilient connection between the cover and the container thereby assuring an effective fluid seal therebetween. While the construction of the present invention is one of general utility, it is particularly applicable to portable beverage containers of the Thermos type frequently utilized by airlines for passenger service.

It is an object of the present invention to provide a cover fastening means for containers which will effect a fluid-tight seal between the cover and the container thereby preventing loss of fluid even when the container is shaken or pivoted.

A further object of the invention is to provide a means for effecting such a fluid-tight seal between the cover and the container which will permit greater latitude in the use of gaskets of variable thickness and which permits greater manufacturing tolerances.

A more particular object of the invention is to provide a cover fastening arrangement whereby the cover is resiliently held in place by means adapted to place the seal under pressure and which is arranged so as to provide an effective seal whether heavy or thin gaskets are utilized.

A further object of the invention is to accomplish the first named aim with a fastening means which is simple and easy to engage and disengage and which employs a minimum of manually manipulated members so that the normal usage of the container is not hindered in any way and does not require unusual strength or long periods of time to operate.

A further object of the invention is to provide a construction of the character referred to which is economical and convenient to manufacture and assemble and one which will be sufficiently rugged to be free from breakage and malfunctioning over long periods of use.

Other objects will be in part obvious and in part pointed out more in detail hereinafter.

The invention accordingly consists in the features of construction, combination of elements and arrangement of parts which will be exemplified in the construction hereafter set forth and the scope of the application of which will be indicated in the appended claims.

In the drawing:

Figure 1 is a top view of a container with the cover in place, said container and cover embodying the cover fastening means of the present invention;

Fig. 2 is a partial side view of the construction; and

Fig. 3 is a fragmentary cross sectional view taken along the line 3—3 of Fig. 1.

2

Referring to the drawing, the cover fastening means of the present invention is shown embodied in a generally rectangular portable beverage container 10 of a type widely utilized by airlines for transporting coffee and the like. The container 10 is provided with an outlet faucet 11 at the bottom thereof and is formed with a rectangular filler opening 12 at the top defined by the downwardly extending or turned in flange 13 around the periphery thereof.

The cover 14 is also rectangular in shape and is provided with a downwardly extending center portion 15 adapted to be received within the filler opening 12. The cover 14 is flanged outwardly at 16 so as to overlie a resilient gasket 17 which, for example, may be formed of rubber extending around the periphery of the opening 12. The cover 14 is provided with a centrally located pivoted handle 18 by means of which the cover may be lifted from the opening or replaced thereon.

The cover 14 is held in place, in accordance with the invention, by fastening means adjacent each of the corners of the cover utilizing a plurality of flexible shafts 20. In the preferred embodiment, the shafts 20 are formed of spring steel so as to provide a high degree of resiliency and flexibility.

The construction at either end of the cover 14 is the same and therefore, in the interests of brevity and simplicity of presentation, the construction at only one end has been shown in detail. Each shaft 20 is received in a cylindrical passageway 21 extending transversely through the cover 14 and the diameter of the passageway 21 is greater than the diameter of the shaft 20. For convenience of fabrication and assembly, each shaft 20 may be formed of two interlocking portions 22 and 23 which are pinned at the center to a tongue 24 which serves as a handle for turning the shaft 20. The top of the cover 14 is provided with depressed areas 26 to accommodate the handles 24.

The passageways 21 are deformed intermediate their ends at 27 and 28 to form raised bearing surfaces for the shafts 20 which rotatably position the shafts along the top of the passageways 21 and provide sufficient space for the downward flexing of the ends of the shafts 20, as shown in Fig. 3 and as explained more fully hereinafter.

Pivotedly secured to the container 10 adjacent the ends of the shafts 20 by means of brackets 30 are a plurality of bails 31 which, when the shafts 20 are turned through approximately a half revolution by means of handles 24 from the position shown in the drawing, may be readily flipped over the ends of the shafts to the position shown in the drawing, or may be readily disengaged therefrom. The ends of the shafts 20 are formed with eccentric extensions 32

which, when the shafts are turned to the position shown in the drawing by means of the handles 24, places the bails 31 under tension sufficient to flex the ends of the shafts 20 downwardly as shown in Fig. 3. The eccentric extensions 32 are also provided with a radial projection 33 for preventing the bails 31 from slipping off the ends of the eccentric extensions 32 when under tension.

The operation of the fastening means of the present invention is relatively simple and requires little time or effort. When it is desired to remove the cover 14 from the container 10, the handles 24 are quickly turned inwardly to a position slightly less than 180° from that shown in the drawing, which turns the eccentric extensions 32 and the radial projections 33 so as to remove the tension from the bails 31 and to permit the bails to be easily flipped off the ends of the extensions 32. Thereupon, the cover 14 may be readily removed from the container as by grasping the handle 18 thereon. When the cover 14 is replaced in position on the container 10, the bails are again flipped over the ends of the extensions 32 and the shafts are returned to the rotated position shown in the drawing by turning the handles 24 to the outwardly extending position shown in the drawing. Immediately upon this happening, the bails 31 are brought under tension by the eccentric extensions 32 which is sufficient to flex the ends of the shafts 20 downwardly as illustrated in Fig. 3. The resultant pressure between the cover 14 and container 10 acting upon the intermediate resilient gasket 17 insures a fluid-tight seal between these members.

It thus will be seen that there has been provided, in accordance with the invention, a cover fastening means for containers, such as beverage containers, which is simple and easy to operate and which provides a fluid-tight seal between the cover and container at all times. The above-described arrangement gives greater latitude in the use of gaskets of variable thickness and permits greater manufacturing tolerances so that the gasket will seal at all times irrespective of gasket thickness within normal manufacturing tolerance ranges. In the event a heavy gasket is used, the arrangement for placing the gasket under pressure is such as to permit the operator to secure the cover with a minimum of effort and, in the event a thin gasket is utilized, a tight gasket seal is assured.

By reason of the fact that the operating latch or handle on each end of the container cover locks or seals the gasket at that end of the container, a minimum of two handles is required to be manipulated in order to lock the four corners of the container as compared with the use of four operating handles which normally would be required to obtain such a locking action.

At the same time, the arrangement is of simple and economical construction so that the cover fastening means may be easily and economically manufactured and assembled. Moreover, none of the parts are susceptible to breakage under normal operating conditions so that a long useful life without need for replacement or repair is assured.

As many changes could be made in the above construction and many apparently widely different embodiments of this invention could be made without departing from the scope thereof, it is intended that all matter contained in the above description or shown in the accompanying draw-

ings shall be interpreted as illustrative and not in a limiting sense.

It is also to be understood that the language used in the following claims is intended to cover all of the generic and specific features of the invention herein described and all statements of the scope of the invention which, as a matter of language, might be said to fall therebetween.

I claim as my invention:

1. Cover fastening means for containers having an opening therein and a removable cover member for closing said opening, comprising a highly flexible shaft journaled on the cover intermediate its ends with the ends extending outwardly from the cover member and spaced laterally from the cover so as to permit the ends of the shaft to be flexed toward the cover, a plurality of bails pivotally mounted on the container for movement to and from engaging position about the ends of the shaft, means for turning the shaft, said extending ends of the shaft being eccentrically formed so as to permit said bails to be easily engaged and disengaged from the ends of the shaft when the shaft is in one rotated position and having a surface sufficiently offset from the axis of the shaft to place the engaged bails under sufficient tension to cause deflection of the ends of the shaft toward the cover when the shaft is turned to a second rotated position, and a radial projection on each end of the shaft for preventing disengagement of the bails when the shaft is turned to said second rotated position, said flexible shaft and bails forming a resilient fastening for the cover.

2. Cover fastening means for containers having an opening therein and a cover for said opening, comprising means in the cover forming a transverse generally cylindrical passageway, a flexible shaft of smaller diameter than said passageway positioned within said passageway with its ends extending outwardly therefrom, said passageway being deformed intermediate its ends to rotatably support the central portion of the shaft adjacent the top of the passageway and to provide a clearance between the ends of the shaft and the bottom of the passageway to permit flexing of the shaft, a handle for turning the shaft, and a plurality of connecting means secured to the container and adapted to be moved into and out of engagement with the ends of the shaft, said ends of the shaft being formed with an offset camming surface adapted to engage the connecting means and constructed and arranged so as to place said connecting means under sufficient tension to flex the shafts when the shafts are turned to a predetermined rotated position.

3. Cover fastening means for containers having an opening therein, a removable cover for said opening, and a resilient gasket between the cover and the periphery of the opening, comprising means in the cover forming a transverse passageway therethrough, a flexible shaft of smaller diameter than said passageway positioned within said passageway with its ends extending outwardly therefrom, said passageway being deformed adjacent the center of the shaft and spaced from its ends to provide bearing surfaces positioning the outer portion of the shaft adjacent the top of the passageway and providing a clearance between the ends of the shaft and the bottom of the passageway to permit downward flexing of the ends of the shaft, a handle fixed to the shaft intermediate its ends for turning same, said cover being provided with an opening extending into said passageway to receive said

handle, a plurality of bails pivotally secured to the container and adapted to be pivoted over the ends of the shaft, said ends of the shaft being formed with offset cam surfaces constructed and arranged so as to permit said bails to be easily engaged and disengaged from the ends of the shaft when the shaft is in one rotated position and for placing the engaged bails under sufficient tension to flex the shaft when the shaft is turned to a second rotated position, and a radial projection on each end of the shaft to prevent disengagement of the bails when the shaft is in said second rotated position.

HARRY M. BADGER.
